UNITED STATES PATENT OFFICE.

CHARLES J. KOCH, OF EASTON, PENNSYLVANIA.

COUNTER-REFRIGERATOR.

1,289,815.

Specification of Letters Patent.

Patented Dec. 31, 1918.

Application filed October 5, 1914. Serial No. 865,156.

To all whom it may concern:

Be it known that I, CHARLES J. KOCH, a citizen of the United States, residing at Easton, in the county of Northampton, State of Pennsylvania, have invented certain new and useful Improvements in Counter-Refrigerators; and I do hereby declare the following to be a full, clear, and exact description of the invention, such as will enable others skilled in the art to which it appertains to make and use the same.

This invention relates to improvements in refrigerators, and particularly to counter refrigerators.

15 One object of the invention is to provide a novel counter refrigerator in which butter, cheese or lard can be handled in an easy and sanitary way.

Another object is to provide a device of 20 this character by means of which the material can be handled and cut outside of the refrigerator without the loss of cold air from the interior of the refrigerator.

Other objects and advantages will be apparent from the following description when taken in connection with the accompanying drawings.

In the drawings:

Figure 1 is an elevation of a refrigerator 30 made in accordance with my invention.

Figure 2 is a vertical sectional view on the line 2—2 of Figure 1.

Fig. 3 is a horizontal sectional view on the line 3—3 of Fig. 1.

35 Fig. 4 is a horizontal transverse sectional view through the refrigerator showing the refrigerator door in open position so that access may be had to the cheese.

Fig. 5 is a fragmentary inverted perspective view of a portion of the platform and the door 12 to better show the lugs and eyes.

Referring particularly to the accompanying drawings, 10 represents a suitable cabinet which is provided with the glass panels 11 to permit a view of the interior while at the same time cold air is prevented from escaping. A door 12 also provided with a glass panel is carried in the front of the cabinet and has on its lower inner face a pair of outwardly extending eye members 13. A quadrant-shaped platform 14 is disposed to move in the doorway and has a pair of depending lugs 15 which are disposed in the eyes 13 and support one of the flat sides of 55 the platform against the inner face of the

door, the other flat side being disposed within the cabinet. On the platform is mounted a turn table 16 on which is adapted to be supported a piece of cheese or butter or a receptacle containing lard. Secured to the bottom of the platform at the angle formed between the inner straight side and the inner end of the curved side is a caster wheel 17 which bears on the floor of the cabinet and supports the inner end of the platform during its inward and outward movement when the door 12 is closed or open. Hinged to the inner side of the front wall of the cabinet, at a point adjacent the hinged connection of the transparent door 12 is a door 18 which is formed from a sheet of glass. The lower edge of this door, and at the outer end, is disposed between a pair of vertically extending pins 20 which holds the door in proper position on the platform to move therewith, as the door 12 is opened and closed. The pins further form guides for the auxiliary door, which, when moved on its hinges, will have a slight transverse movement, and as the door is relatively smooth, it will engage with the pins at each side thereof, and the movement in this direction will not be interfered with and in the end it will be aided. When the door 12 is opened, the platform 14 will be disposed outside of the cabinet and the door 18 covering the entrance opening of the cabinet. This will effectively stop any cold air from escaping from the cabinet and at the same time disposes the cheese or butter or other commodity outside of the cabinet in a position to be easily cut or otherwise handled. When the door 12 is moved into closed position, the platform moves inwardly carrying the door 18 with it.

It will be noted that the lugs 15 loosely engage in the eyes 13 so that the platform can be readily taken out when it is desired to clean the same, the door 18 remaining in position within the cabinet.

Attention is called to the fact that the pins 20 are removable from the platform, whereby the glass door 18 may be swung farther inwardly and permit the platform to be swung outwardly with the door 12 and thus render the removal of the lugs 15 from the eyes 13, and the complete removal of the platform. The peculiar construction and arrangement of the lugs and eyes is clearly shown in Fig. 5.

110

Attention is also directed to the fact that as the door 12 is swung outwardly and the platform is drawn through the doorway therewith, the glass door 18 will be swung 5 on its hinges into such position as to completely close the doorway, while at the same time the outer portion of the door 18 will be permitted a free sliding movement between the pins 20, to compensate for the difference 10 in positions of the pivotal points of the two doors.

The depending lugs 15, after having been passed downwardly through the eyes 13 receive transverse removable pins 21 there- 15 through, these being clearly shown in Figs. 2 and 5. By providing a glass panel in the door 12 and forming the door 18 of glass, the interior of the cabinet is at all times visible from the outside, so that it can be 20 known whether the cabinet is clean or not.

Copies of this patent may be obtained for five cents each, by addressing the "Commissioner of Patents.
Washington, D. C."

What is claimed is:

A cabinet having a door opening, an exterior closure for the opening, a shelf connected to said closure and movable therewith into and part way out of the cabinet when 25 the closure is moved into and out of closing position, said shelf extending laterally beyond one wall of the opening, a hinged closure for the opening within the cabinet resting slidably upon said laterally extending 30 portion of the shelf, and spaced pins upon the shelf, between which the second named closure stands for lateral movement with and slidable movement of the shelf.

In testimony whereof I affix my signature, 35 in the presence of two witnesses.

CHARLES J. KOCH.
